UNITED STATES PATENT OFFICE.

JAMES F. STANLEY, OF INDIANAPOLIS, INDIANA, ASSIGNOR TO LAVELLE FOUNDRY COMPANY, OF INDIANAPOLIS, INDIANA, A CORPORATION OF INDIANA.

MOLDER'S FLASK.

Application filed October 8, 1925. Serial No. 61,355.

It is the object of my invention to produce a molder's flask in which the two parts may be put together accurately and easily, and may be separated easily without jar-
ring, tilting, or lateral swaying; to provide an improved construction of flask generally, and especially an improved construction of tapered flask; and to provide more efficient means for preventing the sand from dropping out of the cope when the latter is lifted from the drag, especially in a tapered flask.

In carrying out my invention, I provide the drag with two exterior upstanding par-
allel pins, desirably round pins, the inner surfaces of which co-operate with guide-
plates adjustably mounted on the sides of the cope to guide the movements of the two parts of the flask as they are put together
and taken apart. One important feature of my invention is the adjustable mounting of these guide-plates. The cope is also pro-
vided with finger-grip parts in suitable proximity to the upstanding pins from the drag, so that in lifting the cope from the drag the molder may rest his hands on the ends of the pins with his fingers gripping these finger-grip parts, so that a long initial lift of the cope may be obtained by a mere closing of the molder's hands, and without interference from the guide-plates. To facilitate this further, I desirably provide special slide-plates, which are carried by the cope but relatively movable thereon and co-
operate with the outer sides of the upstand-
ing pins from the drag to provide a further guiding means for the movement of the cope and also to provide a wider area of support for the molder's hands than is provided by the ends of the pins themselves, although the molder's hands may still be supported by the upstanding pins through the medium of these slide-plates.

These guiding and lifting means are applicable to flasks of various constructions, but particularly so to tapering flasks, where the separating movement between the two parts must be even more accurate than in non-tapering flasks. Therefore, my invention contemplates also a special construction of such tapering flask, with round corners; which round corners not only save sand but also facilitate the removal of the flask from the mold without breaking the latter.

55 While round-cornered flasks have hereto-

fore been thought desirable, their cost has been prohibitive; and my invention involves a more effective and less expensive process of making such flasks and maintaining them in shape, so that the molds produced by a number of flasks may all be of uniform size and shape to receive, interchangeably, suitable tapered jackets which are put upon them prior to the pouring of the iron into the molds. This method of making the flasks consists in casting them of suitable malleable metal, as aluminum, aluminum alloys, or brass, and shaping the cast molds accurately by forcing them on to a tapered mandrel of suitable size and shape. Fur-
ther, my invention includes a special con-
struction of withdrawable flange for pro-
jecting under the sand in the cope to hold such sand in place when the cope is lifted, and means for operating such flange to draw it from beneath the sand when desired.

The accompanying drawings illustrate my invention: Fig. 1 is a plan of a flask embodying my invention, with the cope in place on the drag, and with the sand-holding withdrawable flange of the cope in its inner or sand-holding position; Fig. 2 is a plan of the cope inverted, with the sand-holding withdrawable flange in its outer or sand-releasing position; Fig. 3 is an elevation of the flask shown in Fig. 1; Fig. 4 is an enlarged vertical central section through one side of the flask at the guiding and positioning means, with the cope resting on the drag, the section being taken on the line 4-4 of Fig. 7; Fig. 5 is a view similar to Fig. 4, but with the cope partly lifted from the drag; Fig. 6 is a fragmental elevation of the guiding and positioning means shown in Figs. 4 and 5, as viewed from the right of Fig. 4; Fig. 7 is a fragmental section on the line 7-7 of Fig. 4; Fig. 8 is a fragmental section corresponding to a portion of Fig. 4 at the junction of the drag with the cope, showing the sand-holding withdrawable flange withdrawn; and Fig. 9 is a view, on a reduced scale, showing the flask on the forming mandrel.

The flask, as usual, is made of two parts, the lower part or drag 10, and the upper part or cope 11. These two parts are made internally tapering, as frustums of the same round-cornered rectangular pyramid, for the corners of the flask are rounded; and are shaped so that the internal faces of the

110

flask and cope will be continuations of each other when the flask and cope are together, as appears most clearly from Fig. 4. The flask and cope are desirably made of a relatively thin shell of cast metal, with reinforcing flanges 12, 13, 14, and 15 at their upper and lower edges. The cast metal used is malleable, and desirably one that takes a relatively smooth cast surface, such as aluminum and its alloys and brass. The shells forming the drag and cope are sufficiently light so that they may readily be hammered into accurate shape over a mandrel 16 (Fig. 9) having its exterior surface in the shape of the round-cornered pyramid of which the inner surfaces of the drag and cope are to constitute frustums. In this way, the drags and copes may be made and kept accurate to the same shape and size of round-cornered pyramids, so that the molds produced in such flasks, or in a number of such flasks, are all uniform, and may interchangeably and tightly receive suitable slip-jackets of the same corresponding round-cornered pyramidal shape to hold the molds together against the internal pressure created when they are poured. The slip-jackets may be kept in shape on the same mandrel. The mandrel 16 is desirably considerably longer than a flask, so that a single mandrel may serve for a number of different sizes of flasks and slip-jackets.

This accurate shaping of the molds may thus be done comparatively cheaply, thus making it possible to form such round-cornered molds without expensive machine operations which have heretofore made them prohibitive.

To make possible this accurate shaping of the final molds, as well as for simplifying the work of the molder and saving him labor, it is necessary to provide accurate guiding and positioning means to control the relative positions and movements of the cope on the drag. To this end, I provide on opposite outer sides of the drag 10 two horizontally projecting flanges 20, which each receives and holds rigidly an upwardly projecting pin 21. The mounting of the two pins 21 in the two flanges 20 is such that such pins are parallel, and are substantially perpendicular to the plane of separation between the drag and cope. The pins 21 are desirably round pins, and their mountings in the flanges are by any convenient shouldered mounting which permits the pins 21 to be rigid with the drag.

The inner sides of the pins 21 co-operate with long guide-plates 22 mounted on the cope 11. There are two of these guide-plates 22, one for each pin 21; and they are supported on flanges 23 projecting from two opposite sides of the cope. The guide-plates 22 have concave guiding faces which co-operate with the inner sides of the pins

21 and as shown are in the form of segments of cylinders of slightly less than 180° ; and the axes of these cylinders are respectively substantially co-incident with the axes of the pins 21 when the cope is on the drag 70 or is being put thereupon or removed therefrom. To obtain this mounting, the upper faces of the flanges 23 are machined to co-operate with the lower faces of flanges 24 which project from the guide-plates 22 away 75 from the pins 21; and each flange 24 is clamped to the corresponding flange 23 by two clamping bolts 25. At least one of the flanges 23 and 24 has slots 26 for such clamping bolts 25, which slots are transverse to the face of the cope to permit adjustment of the clamping plate 22 as a whole toward and from the cope. To obtain such adjustment, the flange 24 of each guide-plate 22 has two upstanding ears 27, which receive 80 thrust-screws 28 for bearing against the outer face of the cope 11, desirably on a machined spot 29. The thrust-screws 28 may be provided with suitable lock-nuts 30 if desired. By loosening the clamping bolts 25, the thrust-screws 28 may be adjusted as desired to get the proper co-operation between the concave faces of the guide-plates 22 and the inner faces of the pins 21.

To facilitate lifting the cope from the drag, the flanges 23 are continued around the pins 21, to the outer sides thereof, of course with suitable openings for such pins. These outwardly continued flanges 23 provide convenient finger-grips, for the molder's fingers to grasp in lifting the cope; and enable him to do so by a mere closing movement of his fingers, since he can rest the palms of his hands on the ends of the upstanding pins 21. It is possible to get a long initial lift of the cope in this way; because, since the guide-plates 22 co-operate with the inner faces of the pins 21, the upper ends of such guide-plates may pass by the molder's hands without interference. To make this lifting 105 still easier, and especially to protect the molder's palms, I desirably slidably mount slide-plates 35 in the flanges 23, preferably in the pin-receiving holes of such flanges 23 to co-operate with the outer sides of the pins 21. These slide-plates 35 are relatively slideable vertically in the flanges 23 as is indicated in Figs. 4 and 5. Desirably the slide-plates 35 have upper and lower limit-flanges 36 and 37 to limit the sliding movement in 110 the flanges 23. The slide-plates 35 are also desirably semi-cylindrical in shape to fit the outer sides of the pins 21, and to be guided by the edges of the guide-plates 22. The downward movement of the slide-plates 35 125 on the pins 21 is suitably limited; so that the upper flanges 36 of such guide-plates will serve as rests for the molder's palms, thus providing a broader area than is provided by the ends of the pins 21 and so easing the 130

pressure on his palms, when he lifts the cope from the drag by the aforesaid finger movement. Such limit is desirably provided by inwardly projecting cap-flanges 38 on the slide-plates 35 in position to engage the upper ends of the pins 21 and thus to hold the slide-plates raised as shown in both Figs. 4 and 5, even though the cope is lowered as shown in Fig. 4. Pairs of guide-pins 39 projecting downward from the flange 36 through guide holes in the extended flange 23 to rest on an extension of the usual pattern plate may also be provided; and these may serve to limit or to help limit the downward movement of the slide-plates 35 on the pins 21.

By reason of the guide-plates 22 and slide-plates 35, it becomes possible to lift the cope accurately and gently from the drag, and to replace it accurately and gently on the drag, with a substantially straight-line movement, without tilting or jarring the cope or swaying it from side to side. This makes for better molds, by requiring less skill and care on the part of the molder and by positively preventing any carelessness or unskillfulness on the molder's part from causing such tilting, swaying, or jarring.

For the same reason of facilitating the molder's work the flanges 20 of the drag desirably have outwardly projecting portions 40, to provide finger grips which the molder may conveniently grasp with his fingers when he desires to lift the flask as a whole from the completed mold.

The use of a tapered mold makes the sand within the cope more prone to drop out of the cope when the latter is lifted from the drag. To prevent this, I provide a withdrawable flange 45 on that face of the cope which co-operates with the face of the drag. This withdrawable flange is made in two parts, each extending along two adjacent sides of the cope face, as is clear from Fig. 2. These two flange-parts are fastened to the cope flange 14 by headed screws 46, which project through undercut slots 47 provided in the parts of the flange 45. All the slots 47 in each part of the flange 45 are parallel, and they are oblique to the sides of the flask so that the movement permitted by such slots causes that part of the flange 45 as a whole to be moved inward or outward with relation to both the corresponding sides of the cope. That is, the obliqueness of the slots 47 is such that those slots are transverse to the line of division between the two parts of the flange 45. To obtain the movement of each part of the flange 45, that flange-part is provided at the junction between its two sides with a slot 48 whose direction is transverse to the direction of the slots 47; and this slot 48 receives an eccentric pin 49 on a rotatable shaft 50 mounted in the flanges 14 and 15 and operable by a

handle 51. By turning the handle 51 from the position shown in the lower right-hand corner of Fig. 2 to the position shown in the upper left-hand corner of such figure, the eccentric pin 50 is moved outward to cause the associated part of the flange 45 to be correspondingly drawn outward to sand-releasing position, as permitted by the slots 47; while by the reverse movement of the handle 51 the flange part is moved inward to sand-holding position. That is, when the handle 51 is moved to the position shown in Fig. 1 and in the lower right-hand corner of Fig. 2, the withdrawable flange 45 is projected inward past the surface of the round-cornered pyramid formed by the inner face of the cope, as is indicated in Figs. 4 and 5; whereas when the handle 51 is moved to its other position, shown in the upper left-hand corner of Fig. 2, the flange 45 is withdrawn so that its inner edge does not project inward beyond the surface of such pyramid, as is indicated in Fig. 8.

The flange 45 is made of substantial thickness, for rigidity, and so that the slots 47 may be undercut to receive the heads of the screws 46. However, it is usually desirable that that part of the flange which projects inward beyond the surface of the pyramid of the inner surface of the cope should be of less thickness. Therefore, I cut away the upper inner corner of the withdrawable flange 45, as is clear from Figs. 4, 5, and 8, to provide merely a thin sand-retaining ledge. The cutting away is desirably in the form of a concave chamfer. This concave chamfer makes a rounded corner between the sides and the bottom of the cope-part of the completed mold.

In addition, it is desirable to provide notches 55 in the inner edges of the withdrawable flange 45. These leave vertical ridges of sand in the completed mold across what would otherwise be a completely encircling equatorial channel around the mold at the junction of the cope-part with the drag-part thereof. In the event of a "bust-out" in pouring, in molds without these ridges, the iron would run completely around this channel beneath the enclosing slip-jacket; but the ridges limit such unwanted flow of iron to the channel-portion between two adjacent ridges.

In operation, the flask is filled with sand to embed the pattern in the usual manner. During the filling of the cope, the withdrawable flange 45 is desirably in its inward or sand-holding position. When the cope has been suitably filled, the operator grasps the flanges 23 of the cope as indicated in Fig. 4, with his palms resting on the flanges 36, and by a finger movement lifts the cope from the drag, as is indicated in Fig. 5. During this movement, the flange 45 effectively holds the sand in the cope, and the

guide-plates 22 and slide-plates 35 effectively prevent tilting and swaying of the rising cope. After the cope has been brought to the position of Fig. 5, it is lifted further by 5 the usual arm movement of the molder. Then the pattern is removed, and the cope is put back on the drag. In putting the cope back on the drag, the reverse of the aforesaid movement takes place, the molder first putting 10 the cope over the drag with the slide-plates 35 and guide-plates 22 on the pins 21, during which time his hands and fingers hold the flanges 23 and 36 in engagement, and then opens his fingers to let the cope 15 gently down on the drag, without tilting or swaying. Then the withdrawable flange 45 is withdrawn to sand-releasing position. Then the operator grasps the projecting portions 40 of the flanges 20, and lifts the flask 20 as a whole from the mold. The mold may now receive one of the interchangeable slip-jackets provided for that purpose, and is then ready for pouring.

I claim as my invention:

25 1. In a molder's flask, the combination of a drag, a cope, two parallel pins projecting upward from sides of the drag, guide-plates on corresponding sides of the cope for co-operating with the inner sides of said pins, and finger-grip flanges on said cope in position to receive the molder's fingers when he puts his palms on the upper ends of said pins.

35 2. In a molder's flask, the combination of a drag, a cope, two parallel pins projecting upward from sides of the drag, guide-plates on corresponding sides of the cope for co-operating with the inner sides of said pins, finger-grip flanges on said cope in position 40 to receive the molder's fingers when he puts his palms on the upper ends of said pins, and slide-plates slidably mounted in said finger-grip flanges to co-operate with the outer sides of said pins, said slide-plates 45 having means to limit the movement of the slide-plates on said pins to less than that of the guide-plates and cope on said pins and furnishing palm-rests for the molder's palms when he puts them on the pins.

50 3. In a molder's flask, the combination of a drag, a cope, two parallel pins projecting upward from sides of the drag, guide-plates on corresponding sides of the cope for co-operating with said pins, finger-grip flanges 55 on said cope in position to receive the molder's fingers when he puts his palms on the upper ends of said pins, and slide-plates slidably mounted in said finger-grip flanges to co-operate also with said pins, said slide- 60 plates having means to limit the movement of the slide-plates on said pins to less than

that of the guide-plates and cope on said pins and furnishing palm-rests for the molder's palms when he puts them on the pins.

4. In a molder's flask, the combination of 65 a drag, a cope, two parallel pins projecting upward from sides of the drag, and guide-plates on corresponding sides of the cope for co-operating with the inner sides of said pins, said pins being round and the co-operating surfaces of said guide-plates being correspondingly concave.

5. In a molder's flask, the combination of 75 a drag, a cope, two parallel pins projecting upward from sides of the drag, said cope having horizontally projecting flanges on sides corresponding to the pin-carrying sides of the drag, guide-plates co-operating with said pins and having supporting flanges supported on the flanges on the cope-sides, 80 clamping bolts for clamping the guide-plate flanges to the cope flanges, said clamping-bolts having a slotted mounting in one of said flanges to permit adjustment, and thrust screws mounted in said guide-plates 85 for bearing against the cope-sides to produce such adjustment.

6. In a molder's flask, the combination of 90 a drag, a cope, two parallel pins projecting upward from sides of the drag, guide-plates on corresponding sides of the cope for co-operating with the inner sides of said pins, said pins being round and the co-operating surfaces of said guide-plates being correspondingly concave, said cope having horizontally projecting flanges on sides corresponding to the pin-carrying sides of the drag, guide-plates co-operating with said 95 pins and having supporting flanges supported on the flanges on the cope-sides, 100 clamping bolts for clamping the guide-plate flanges to the cope flanges, said clamping-bolts having a slotted mounting in one of said flanges to permit adjustment, and thrust-screws mounted in said guide-plates 105 for bearing against the cope-sides to produce such adjustment.

7. In a molder's flask, the combination of 110 a drag, a cope, two parallel pins projecting upward from sides of the drag, and guide-plates on corresponding sides of the cope for co-operating with the inner sides of said pins, said pins being round and the co-operating surfaces of said guide-plates being correspondingly concave, said guide-plates being 115 arranged to co-operate with the inner sides of such pins.

In witness whereof, I have hereunto set my hand at Indianapolis, Indiana, this 3rd day of October, A. D. one thousand nine 120 hundred and twenty-five.

JAMES F. STANLEY.
